PUMP FOR PROPELLING PELLETS INTO OIL WELLS FOR TREATING THE SAME

Edward N. Jones, Pettus, Tex.

Application March 24, 1954, Serial No. 418,399

6 Claims. (Cl. 166—95)

The present invention relates to a means for introducing oil well tubing treating material in the form of dry pellets into the casing annulus of an oil well through the well head connections.

The primary object of the invention is to provide a means for force pumping dry, scale and corrosion treating pellets into the side entrances of the Christmas tree of the well which will propel the pellets into the casing annulus under high pressures without interrupting the flow of the well.

A highly important object of the invention is in the provision of a dry treating pellet propelling mechanism to be attached to the well head connections wherein the pellets are maintained under well pressure at all times prior to their propulsion into the casing annulus or the well tubing.

A further object of the invention is in the provision of a pump assembly for propelling the pellets including a pellet injecting barrel and propulsion mechanism which initially seats lightly against the pellets to be injected while moving the pellet forwardly through the injection barrel, than seats progressively more forcibly against the pellet prior to releasing the pellet to afford the necessary impetus to cast the pellet into the well casing annulus.

Yet another object of the invention ancillary to the preceding object is the provision of a pellet ejection assembly including a pellet reservoir which will release pellets singly into the ejection barrel whereby the balls or pellets are individually released into the casing annulus.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a front elevational view of the Christmas tree on the well head to which the pumping mechanism constituting the present invention is attached;

Figure 2 is a side elevational view of the pumping mechanism per se with certain parts being broken away and shown in cross section for clarity of detail;

Figure 3 is an enlarged cross sectional view of the pump injection barrel disclosing the manner in which the pellet propulsion mechanism is compressively seated against a pellet to be injected;

Figure 4 is a view similar to Figure 3 disclosing the pellet being discharged from the injection barrel by the propulsion mechanism;

Figure 5 is a cross sectional view of a portion of the injection barrel taken substantially along section line 5—5 of Figure 2;

Figure 6 is an enlarged side elevational view of the pellet propulsion mechanism per se; and

Figure 7 is an enlarged view of a portion of a well head connection on the Christmas tree with parts being broken away to disclose the manner of discharging the pellets into the casing annulus of the well.

2

In Figure 1 is shown a typical installation of the pump and ball ejecting mechanism constituting the present invention on a producing well. In this figure the well casing 10 is shown extending above the ground level with the well head connections being applied thereto in the form of the Christmas tree 12. To the side opening well head connection 14 of the Christmas tree 12 leading into the casing annulus 18 (note Figure 7) the pump construction 20 constituting the present invention is attached.

The pump itself is of the conventional, reciprocating piston type and is designated by the numeral 22. Air supply line 24 leads from the pump body 22 through a suitable pressure regulator 26 into the well head itself whereby the pump may be actuated directly by the pressure of the well gases. The pump mechanism 20 includes a pellet injecting assembly 28 attaching the pump body to the well head connection 14.

The manner of injection of the treating pellets into the casing annulus 18 by the pumping mechanism 20 is illustrated in Figures 2 to 6.

In Figure 2, the pump body 22 is shown with a portion cut-away to disclose the piston 30 slidably and reciprocably disposed therein, the piston 30 being reciprocated by means of the pressurized gas passing through the line 24 into the pump body. A suitable valve arrangement is provided within the pump body 22 for alternately applying pressure to opposite faces of the piston 30. Although the pump valve assembly is not shown in the drawings, it is to be understood that this mechanism is conventional as is the pump body itself and except for its utility in the combination is not significant to the present invention. The piston 30 is provided with a piston rod 32 projecting reciprocably through one end of the pump body 22.

The ball injection assembly 28 includes an injection barrel 34 suitably coupled at one end to the end of the pump body 22 through which the piston rod 32 projects. As shown, this coupling is in the nature of the flange coupling 36 in the embodiment shown. The barrel 34 at its outer end is provided with a longitudinal bore 38 through which the piston rod 32 extends. Suitable packing rings 40 are provided in grooves surrounding the bore 38 and the lubrication chamber 42 likewise opens into the bore 38. Lubrication supply reservoir 43 opens into the lubrication chamber 42 to lubricate the piston rod 32 as it reciprocates within the bore. The barrel 34 is provided with an enlarged counterbore 44 into which the outer end of the piston rod 32 projects. A head 45 is secured to this outer end of the piston rod 32 and is reciprocably disposed within the counterbore 44. The counterbore 44 opens into an enlarged pellet receiving chamber 46 within the barrel 34 which chamber in turn opens into a tubular end portion 48 of the injection barrel 34. The end of the tubular section 48 is provided with external threads 50 for coupling the same to the well head connection 14 of the Christmas tree whereby the injection barrel upon opening of the Christmas tree valve 52 will be maintained under the well pressure.

In this connection, it is to be noted that the surface area of the piston 30 is considerably greater than the surface area of the head 45 at the end of the piston rod 32 whereby the pressure to be exerted against the piston 30 may be considerably less than the well pressure to drive the head 45 forwardly within the injection barrel 34. This is of course important when it is considered that the well head pressure may be anywhere from 1,000 to 10,000 lbs.

One end of the resilient, compression coil spring 54 is coiled onto the head 45 seating in suitable grooves 56 formed therein. The other end of the coil spring 54 is

disposed forwardly of and remote from the head 45 and cup 58 is secured to this end. A short, axially extending rod 60 projects from the forward end of the head 45 terminating intermediate the ends of the coil spring 54. When the pump piston 30 is in its retracted position, the coil spring 54 is expanded within the counterbore 44 and the cup 58 seats adjacent one end of the pellet receiving chamber 46 in the injection barrel 34. In Figure 2, it will be seen that the pellet receiving chamber 46 is of a size sufficient to receive only one pellet 62 at a time.

Within the tubular portion 48 of the barrel 34, communicating with the opposite side or end of the pellet receiving chamber 46 are mounted a plurality of circumferentially spaced spring clips 64 which restrict the passage through this tubular portion of the barrel.

A pellet reservoir 66 extends vertically from the injection barrel 34 intermediate the ends thereof and opens into the pellet receiving chamber 46. Cap 68 ordinarily closes the upper end of the reservoir 66.

In the operation of the device, the piston 30 and consequently the piston rod 32 are initially pressed forward thereby pressing the head 45 forward in the counterbore 44 and also pressing the coil spring in its expanded form 54 forward into contact with a pellet 62 within the pellet receiving chamber 46. Continued pressure against the piston 30 presses the pellet 62 into engagement with the restricting clips 64 within the tubular portion 48 of the barrel 34 thereby causing the spring 54 to compress as the head 45 is continually pressed forwardly.

The spring continues to compress until the position shown in Figure 3 is reached within the short, extending plunging rod 60 contacts the back face of the cup 58 thereby spreading out the clips 64 and pressing the pellet 62 therethrough. As the pellet is pressed through the restricting clips 64, the spring 54 expands and serves to propel the ball or pellet 62 through the well head connection 14 into the casing annulus 18 between the casing 10 and the well tubing 70 as shown in Figure 7.

With this propulsion method, the ball is first lightly touched by the cup 58 with the pressure being progressively applied as the head 45 is moved forwardly to prevent any sudden striking of the pellet which would tend to break up or fracture the pellet. Further, as the head 45, spring 54 and cup 58 move through the pellet receiving chamber 46, additional pellets are prevented from entering the chamber 48 during this movement since the chamber is blocked off by the aforementioned propulsion elements whereby a second pellet cannot enter the chamber until the piston rod 32 is again retracted back into the counterbore 44 its full distance as is shown in Figure 2.

In order to facilitate supplying the reservoir 66, pressure relief valve 72 is provided in the reservoir wall. To resupply the reservoir therefore, valve 52 may be turned to block the passage through the well head connection 14, pressure relief valve 72 opened to exhaust the pressure from within the injection assembly 28 and the cap 68 then removed and the reservoir 66 refilled with pellets.

As shown in the drawings, the pellets 62 are preferably in spherical form although they may be oval, oblong or otherwise shaped, the primary consideration being that they be enabled to make the acute angled turns necessary in injecting them through the well head connections whereby they may be introduced into the well casing annulus or well tubing for the treatment of the tubing against scale and corrosion without interruption of the flow from the well.

The pellets may be composed of any conventional treating agent; however, it is preferred that the treating materials be formed of the composition set forth in Patent No. 2,658,036 for Composition for Preventing Deposition and Corrosion in Oil Well Equipment, issued on November 3, 1953, to Clark D. Core and myself.

From the foregoing, the construction and operation of the device will be readily understood and further explana-

tion is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

What is claimed as new is as follows:

1. A pump construction for dispensing treating pellets into the casing annulus of an oil well comprising a pump and a pellet injection assembly for injecting pellets into the casing annulus through the side of a Christmas tree, said pump including a body having a piston rod extending reciprocably through one end thereof, said injection assembly being attached to said one end and including a pellet injection barrel guidingly receiving said piston rod, means on said barrel for attaching the same to a portion of a Christmas tree communicating with the casing annulus, means in said barrel restricting the passage of a pellet therethrough, and means on said piston rod for propelling a pellet through the barrel, said barrel having an axial bore through one end thereof and a counterbore communicating therewith, said barrel having a tubular passage opening into the other end thereof and a pellet receiving chamber communicating said tubular passage and said counterbore, said pellet propelling means normally seating in said counter-bore, said piston rod being guidingly received in said bore, said propelling means including a head on said piston rod seating within said counterbore, resilient means on said head and extending toward said pellet receiving chamber, a pellet engaging element on said resilient means for ejecting a pellet from said receiving chamber through said tubular barrel.
2. A pump construction for dispensing treating pellets into the casing annulus of an oil well comprising a pump and a pellet injection assembly for injecting pellets into the casing annulus through the side of a Christmas tree, said pump including a body having a piston rod extending reciprocably through one end thereof, said injection assembly being attached to said one end and including a pellet injection barrel guidingly receiving said piston rod, means on said barrel for attaching the same to a portion of a Christmas tree communicating with the casing annulus, means in said barrel restricting the passage of a pellet therethrough, and means on said piston rod for propelling a pellet through the barrel, said barrel having an axial bore through one end thereof and a counterbore communicating therewith, said barrel having a tubular passage opening into the other end thereof and a pellet receiving chamber communicating said tubular passage and said counterbore, said pellet propelling means normally seating in said counter-bore, said piston rod being guidingly received in said bore, said propelling means including a head on said piston rod seating within said counterbore, resilient means on said head and extending toward said pellet receiving chamber, a pellet engaging element on said resilient means for ejecting a pellet from said receiving chamber through said tubular barrel, a pellet reservoir opening into said pellet receiving chamber, said propelling mechanism blocking passage from the reservoir to the chamber during the ejection of a pellet from the chamber.
3. A pump construction for dispensing treating pellets into the casing annulus of an oil well comprising a pump and a pellet injection assembly for injecting pellets into the casing annulus through the side of a Christmas tree, said pump including a body having a piston rod extending reciprocably through one end thereof, said injection assembly being attached to said one end and including a pellet injection barrel guidingly receiving said piston rod, means on said barrel for attaching the same to a portion of a Christmas tree communicating with the casing annulus, means in said barrel restricting the passage of a pellet therethrough, and means on said piston rod for propelling a pellet through the barrel, said barrel having

an axial bore through one end thereof and a counterbore communicating therewith, said barrel having a tubular passage opening into the other end thereof and a pellet receiving chamber communicating said tubular passage and said counterbore, said pellet propelling means normally seating in said counterbore, said piston rod being guidingly received in said bore, said propelling means including a head on said piston rod seating within said counterbore, resilient means on said head and extending toward said pellet receiving chamber, a pellet engaging element on said resilient means for ejecting a pellet from said receiving chamber through said tubular barrel, a pellet reservoir opening into said pellet receiving chamber, said propelling mechanism blocking passage from the reservoir to the chamber during the ejection of a pellet from the chamber, said barrel restricting means being mounted within said tubular passage adjacent said pellet receiving chamber and engaging a pellet upon ejection from the chamber causing said resilient means to compress as a pellet is pressed through the restriction into the tubular passage.

4. A pump construction for dispensing treating pellets into the casing annulus of an oil well comprising a pump and a pellet injection assembly for injecting pellets into the casing annulus through the side of a Christmas tree, said pump including a body having a piston rod extending reciprocably through one end thereof, said injection assembly being attached to said one end and including a pellet injection barrel guidingly receiving said piston rod, means on said barrel for attaching the same to a portion of a Christmas tree communicating with the casing annulus, means in said barrel restricting the passage of a pellet therethrough, and means on said piston rod for propelling a pellet through the barrel, said propelling means including a head on said piston rod seating within said counterbore, resilient means on said head extending toward said passage restricting means, and a pellet engaging element on said resilient means for ejecting a pellet from said barrel.

5. A pump construction for discharging treating pellets into the casing annulus of an oil well comprising a pump and a pellet injecting assembly for injecting pellets into the casing annulus, said pump having a piston rod extending reciprocably through one end thereof, said pellet

injecting assembly being attached to said one end and including a pellet injection barrel into which said rod projects, said barrel having a pellet receiving chamber and an open discharge end, resilient means in said barrel between said discharge end and said chamber restricting passage of a pellet through said discharge end, and means connected to said piston rod for propelling pellets from said receiving chamber through said discharge end, said means including a resilient extension on said rod having a pellet engaging element thereon adapted to compress while forcing a pellet through said resilient passage restricting means.

6. A system for dispensing corrosion preventing pellets and for delivering them into the casing annulus of an oil well, comprising a pellet injection assembly attached to an oil well Christmas tree and including an injector barrel provided with a tubular end portion joined at one side to an opening in the Christmas tree and thereby communicating with the casing annulus of the oil well, and further provided with a pellet receiving chamber and with a counterbore leading from the pellet receiving chamber and having a closed end, a cup applied against a pellet to be injected into the casing annulus, a head reciprocable within the counterbore, said head being resiliently connected with said cup and carrying a push rod coming into contact with said cup only after the head has moved to a predetermined distance within the said counterbore, a piston operated by pressure fluid, connected with a piston rod passing through the closed end of the counterbore and connected with the said head, a resistance means holding the pellet within said tubular endpiece, when pushed by the cup, said push rod when reaching the cup overcoming the resistance of the resistance means and pushing the pellet into the annulus casing.
